UNITED STATES PATENT OFFICE.

GILES H. COOK, OF DES MOINES, IOWA.

ACETYLENE-GAS GENERATOR.

1,015,378.

Specification of Letters Patent.

Patented Jan. 23, 1912.

Application filed March 28, 1910. Serial No. 551,999.

To all whom it may concern:

Be it known that I, GILES H. COOK, a citizen of the United States of America, and resident of Des Moines, Polk county, Iowa, have invented a new and useful Acetylene-Gas Generator for Locomotive-Headlights, Automobiles, Naval Search-Lights, and the Like, of which the following is a specification.

10 This invention relates to and is an improvement on Letters Patent of the United States numbered 685,259 and 685,260 granted to me October 29, 1901.

15 The object of this invention is to provide an improved construction for a carbid basket or container for acetylene gas generators by means of which the basket may be mounted for oscillation and be oscillated by lateral movement or vibration of a locomotive, carriage or vessel on which my generator is employed.

20 My invention consists in the construction arrangement and combination of elements hereinafter set forth, pointed out in my claims and illustrated by the accompanying drawing, in which—

25 Figure 1 is a rear elevation of the complete device. Fig. 2 is an elevation, partly in section, illustrating the construction and 30 mounting of the carbid basket in the carbid generator or generator chamber.

35 My improved carbid basket or container is shown in Fig. 1 applied to a generator in which 10 designates a supporting frame, 11 a cylinder, 12 the water tank having the filling port 13; 14 a pipe connecting the water tank and cylinder, 15 a bracket extending laterally from the frame 10 and having a hand screw 16 mounted therein. The generating chamber 17 is mounted on the upper end of screw 16, and has a flanged cover 18 thereon with a gasket 19 between the cover and the edge of the chamber.

40 20 indicates a pipe connected to cylinder 11 with a valve 21 therein, and 22 a feed pipe connecting pipe 20 and chamber 17.

45 A carbid basket 23 is mounted within and is removable from the chamber 17. The carbid basket 23 is formed with four legs, 50 preferably uniformly spaced throughout its circumference, and two of said legs, 24, 25, arranged diametrically opposite each other,

are of slightly greater length than the other two legs, 26, 27, also arranged diametrically opposite each other. A supply pipe 28 leads 55 through and from the flanged plate 18 to a point above the top of the water tank 12 and thence extends laterally and downward through said water tank and through the top of the cylinder 11. A service pipe 60 29 communicates with and leads from the supply pipe 28.

In practical use the water tank 12 is supplied through the mouth 13 and water flows from said tank through the pipe 14 to the cylinder 11 and fills the latter cylinder to a point above the mouth of the pipe 20. Then water is admitted to the carbid holder through the pipes 20, 22 by opening the needle valve 21, and falls upon carbid contained in the basket 23. When the locomotive, carriage or vessel on which the generator is employed is in motion, the carbid basket 23 will be oscillated and jostled about in the holder to the end that all of the carbid 75 therein will be brought into contact with water dropping from the pipe 22. Gas generated in the chamber 17 is discharged through the pipe 28 into the top of the cylinder 11. 80

I claim as my invention—

1. In an acetylene gas generator, a carbid basket therein, said basket formed with two pairs of legs arranged at right angles to each other, one pair of legs varying in length 85 from the other pair of legs.

2. In an acetylene gas generator, a generating chamber having a flat bottom, a carbid basket in said chamber, said basket having two pairs of legs arranged at right angles to one another, one pair of legs being shorter than the other pair of legs, said carbid basket being seated within the chamber and supported by the legs aforesaid engaging the flat bottom of the chamber, and 90 the basket being oscillated by movements of the chamber. 95

Signed by me at Des Moines, Iowa, this twenty-third day of July, 1909.

GILES H. COOK.
